UNITED STATES PATENT OFFICE.

CHARLES EDWIN BABBITT, OF CINCINNATI, OHIO.

PAPER-WEIGHT AND GUIDE-RULE.

SPECIFICATION forming part of Letters Patent No. 321,672, dated July 7, 1885.

Application filed August 30, 1884. (No model.)

To all whom it may concern:

Be it known that I, CHARLES EDWIN BABBITT, of Cincinnati, in the county of Hamilton and State of Ohio, have invented certain new and useful Improvements in Paper-Weights and Guide-Rulers; and I do hereby declare the following to be a full, clear, and exact description of the invention, such as will enable others skilled in the art to which it pertains to make and use the same.

My invention relates to a combined paper-weight and guide-ruler, especially adapted for the use of book-keepers to facilitate and aid their work.

The invention consists of a combined paper-weight and guide-ruler formed of a strip of metal, gutta-percha, or other suitable material, in combination with a sliding or movable weight, as will be hereinafter fully described, and pointed out in the claims.

In the accompanying drawings, Figure 1 illustrates a plan view of my improved device. Fig. 2 is an edge view of the same. Fig. 3 is a transverse section on the line xx of Fig. 1. Figs. 4 and 5 illustrate a modification.

A represents a ruler formed of a strip of metal or other suitable material, slightly curved downwardly at one end to adapt it to fit snugly between the pages of an account-book, as shown by dotted lines in Fig. 2. This strip A is formed with a central longitudinal groove, a , (preferably of dovetail form in cross-section.) Within this groove is arranged a weight, B, of a form to correspond with the groove, and adapted to slide freely within the latter. The weight B is provided with a finger-piece or knob, b , to facilitate the sliding of the weight.

In Figs. 4 and 5 I have illustrated a modification of the device. In this instance the central groove, a , is omitted, and instead thereof the longitudinal edges of the strip are grooved or guttered, and the weight B is formed with opposite arms or extensions C, whose outer ends, c , are slightly bent to enter the edge grooves of the strip. Thus the weight 45 may be readily moved upon the strip.

It will be understood that the sliding of the weight is for the purpose of keeping it out of the way of the hand of the writer.

I do not limit myself to the precise construction shown, but reserve to myself the right to make such slight changes as may properly fall within the scope of my invention.

Having fully described my invention, what I claim as new, and desire to secure by Letters Patent, is—

1. The combination, with a strip or guide-ruler, of a movable weight, substantially as set forth.

2. The combination, with a guide-ruler curved at one end, as described, of a weight adjustably secured to said ruler, substantially as set forth.

3. The combination, with a grooved ruler or strip, of a weight formed with a finger-piece 65 or knob and adapted to be adjusted upon said ruler, substantially as set forth.

In testimony whereof I have signed this specification in the presence of two subscribing witnesses.

CHARLES EDWIN BABBITT.
